UNITED STATES PATENT OFFICE.

JOSEPH F. COPELAND, OF DREXEL HILL, PENNSYLVANIA.

DRAWING-BOARD.

1,394,538.

Specification of Letters Patent. Patented Oct. 25, 1921.

Application filed May 24, 1920. Serial No. 383,970.

To all whom it may concern:

Be it known that I, JOSEPH F. COPELAND, a citizen of the United States, residing at Drexel Hill, in the county of Delaware and 5 State of Pennsylvania, have invented certain new and useful Improvements in Drawing-Boards, of which the following is a specification.

This invention generally stated relates to 10 drawing boards and has more especial relation to those used by artists, draftsmen and illustrators engaged in making "wash" drawings. It is common practice, in this class of work, to paste the marginal portions 15 of drawing paper to a conventional drawing board with very unsatisfactory results. Primarily, when so applied, it is necessary to cut the paper in order to remove the finished drawing for the reason that the 20 pasted portions firmly adhere to a wooden board. Cutting frequently results in tearing of that portion of the paper containing a drawing. The adhering portions remaining tend to form a raised, uneven surface 25 requiring frequent scraping of the drawing board.

Another disadvantage is that drawing paper so applied tends to bulge or buckle with the result that an undesirable working 30 surface is presented. Frequently the working surface has a tendency to split. For exhibition and shipping purposes a drawing must be stripped from its board and stretched upon a proper mount, and in the 35 event of shipping the mount must be boxed.

The leading object of the present invention is to overcome the above described disadvantageous features and provide a novel form of drawing board attachment of 40 simple, efficient and comparatively inexpensive construction capable of application to boards in use or which may be applied to boards at the time manufactured. Other and further objects will appear hereinafter. 45 The invention consists of the improvements hereinafter described and finally claimed.

The nature, characteristic features and scope of the invention will be more fully 50 understood from the following description taken in connection with the accompanying drawings forming part hereof, and in which:

Figure 1, is a perspective view of my improved drawing board illustrating the manner of assembling same.

Fig. 2, is a fragmentary view in cross-

section, drawn to an enlarged scale, the parts being in assembled position, and

Fig. 3, is a top or plan view of a drawing board embodying features of the invention 60 and illustrating the manner of using same.

For the purpose of illustrating my invention I have shown in the accompanying drawings one form thereof which is at present preferred by me, since the same has been 65 found in practice to give satisfactory and reliable results, although it is to be understood that the various instrumentalities of which my invention consists can be variously arranged and organized and that my invention 70 is not limited to the precise arrangement and organization of the instrumentalities as herein shown and described.

In the drawings 10 designates a conventional drawing board of wood. Fixed to 75 its upper face and extended marginally along at least one end and one side thereof is an edging 11 preferably having a continuous undercut or beveled portion 12 for a purpose to presently appear. For illustrative purposes, I have shown the edging 11 as comprising strips of wood secured to place by suitable means as screws 13. This forms a convenient method of converting a used drawing board into a board embodying features of the invention. In case the attachment of the invention is built into a drawing board at the time of manufacturing, it may be deemed expedient to form the edging as 85 an integral part of the board. It will be 90 noted that the outer edges of these strips are flush with the outer edges of the board 10. Removably fitted to the upper face of board 10 is a mount 14 of suitable fibrous material. In practice excellent results have been 95 obtained by using what is commercially termed compo-board. Those edges of the mount calculated for abutting relation with the edging 11 are beveled as at 15, so that a relative inter-lock is provided. Best results 100 have been obtained by providing an edging upon but two sides of a board and beveling the mount edges accordingly although obviously three sides may be so formed if desired. The remaining sides of the mount, 105

in the present instance two, are secured to the board 10 by suitable means as screws 16. The mount is countersunk to receive the screw-heads and the board is provided with screw-threaded sleeves 17 to receive the 110 screws. Thus the mount may be removed and replaced as desired. The underside of

the mount may if desired be provided with means for suspending the same for exhibition purposes. A ring 18 secured in a countersunk portion 20 adjacent an edge of the mount constitutes an example of such means. A description will now be given of the manner of using the above described board. Drawing paper has first applied to the entire rear surface thereof a coating of suitable paste after which the paper is stretched taut over the mount 14. Practice has dictated that paper so applied will accept wettest washes without buckling or splitting of the drawing paper. Upon completion of a drawing the paper may be readily stripped from the mount 14 for mounting upon a conventional stretcher. Such stripping may be readily effected because while properly adhering for working purposes no such undue adherence is present as when a wooden board is employed. If desired the mount 14 with the drawing adhering may be removed by the loosening of screws 16 with respect to the base or drawing board proper.

Among the advantages claimed for my improved drawing board mention may be made of the following:—

- (a) Buckling, splitting and tearing of drawing paper is eliminated.
  - (b) The mount may be utilized as a stretcher for exhibition and for shipping purposes.
  - (c) When a drawing is shipped adhering to a mount, the drawing is protected against puncture by the backing thus afforded.
  - (d) When several drawings adhering to mounts are shipped together, boxing of the drawings is unnecessary.
  - (e) The mounts may be repeatedly used in that drawing paper readily strips therefrom in an even and uniform manner thus always leaving a smooth surface upon the mount.
- It will now be apparent that I have devised a novel and useful construction which embodies the features of advantage enumerated as desirable in the statement of the invention and the above description and while I have in the present instance shown and described the preferred embodiment thereof which has been found in practice to give

satisfactory and reliable results, it is to be understood that the same is susceptible of modification in various particulars without departing from the spirit or scope of the invention or sacrificing any of its advantages.

What I claim is:—

1. A drawing board comprising a fixed base portion, provided upon a plurality of sides with a marginal raised portion or rim, a fibrous mount removably fitted over said base in abutting relation with said rim, the top of said rim and the top of said mount being flush with one another, and means for securing said mount to place.
2. A drawing board as described in claim 1, characterized by inner beveled edges for said rim and outer beveled edges for said mount.
3. A drawing board as described in claim 1, characterized by screw-threaded sockets in said base and screws for securing said mount to place said screws being accommodated by said sockets.
4. A drawing board as described in claim 1, characterized by means carried by the mount for suspension purposes.
5. A drawing board comprising a base provided upon a plurality of sides with a fixed marginal raised portion or rim the outer faces of which are flush with the outer faces of said base at least one side of said base being free of a raised portion to permit insertion of a mount, a fibrous mount removably fitted upon said base in abutting relation with said rim and means for securing said mount to place.
6. A drawing board comprising a solid base, provided upon a plurality of sides with a fixed raised portion or rim at least one side of said base being free of a raised portion to permit insertion of a solid mount, a fibrous mount removably fitted upon said base in abutting relation with said rim, the exposed side of the mount adjacent the side of the base which is free of a rim being flush with such base side and means for securing mount to place.

In testimony whereof, I have hereunto signed my name.

JOSEPH F. COPELAND.
